SEALED SPARK PLUG ASSEMBLY

Wilfred A. Bychinsky, Flint, Mich., assignor to
 General Motors Corporation, Detroit, Mich., a
 corporation of Delaware

Application April 10, 1948, Serial No. 20,273

8 Claims. (Cl. 174—35)

1

The invention relates to spark plugs and ignition cable connections thereto, particularly of the waterproof type.

The invention has especially advantageous application to spark plugs and ignition cables which are enclosed in metal shielding to prevent interference with nearby radio reception. Shielded spark plugs now in most common use comprise an insulation lined metal barrel which extends upwardly from the base of the plug proper and forms a socket into which the end of the ignition cable is intruded to make contact with the central electrode of the plug. The portion of the ignition cable extending into the socket is generally enclosed in two or more removable sleeves of insulating material, one of which is of rigid construction and carries a metal tip piece including a short helical spring connected to the end of the ignition conductor, and another of rubber or similar material has an integral collar extending outwardly therefrom which serves as a packing at the joint between the end of the plug barrel and the abutting external flange on the end of the cable shielding conduit outside the plug. A coupling nut, having an internal flange interlocked with the conduit external flange and threadedly engaging the plug barrel, secures the parts together.

Difficulty has been encountered in such prior constructions, both with respect to preventing the entrance of moisture into the cable socket of the spark plug, and in obtaining the very high electrical continuity between the spark plug barrel and cable conduit which is necessary for proper radio shielding. After a relatively short period of operation the rubber tends to flow and lose its resiliency, allowing moisture to seep in from the outside between the two abutting shielding members, and from the interior of the cable conduit between the cable and the rubber sleeve. Slight irregularities in the abutting surfaces of the plug barrel and cable conduit, resulting from either damage, warping or original poor machining, destroy the near-perfect mating contact necessary for satisfactory shielding; and while the coupling nut serves as an additional electrical path for the shielding currents, its use as such is only partially effective and is not reliable.

It is therefore an object of this invention to provide a spark plug and ignition cable lead-in assembly incorporating improved means for sealing against the entrance of moisture into the plug.

A further object is to provide such an assembly

2

particularly adapted for radio shielded ignition systems.

Other objects and advantages will become evident from reading the following description, together with the drawing which shows a longitudinal section through a radio shielded aircraft spark plug and cable lead-in assembly embodying the invention.

In the drawing, the spark plug assembly indicated generally by the numeral 1 comprises a metal body or base portion 2, externally threaded at 3 for securement in an engine cylinder head (not shown), an insulating body 4 having an upwardly open cylindrical recess serving as a cable socket 5 at its upper end, a cylindrical metal shielding barrel or shell 6 extending from the base portion 2 above the upper end of the insulating body, and a central electrode 7 extending through the lower part of the insulating body and terminating at its upper end in the bottom of the cable socket 5. The electrode 7 may be of any suitable construction—that shown being provided with an auxiliary spark gap 8 for purposes incidental to the instant invention.

The upper end of the spark plug shielding barrel 6 is provided with an internal flange 9 which extends over the upper end 10 of the insulating body 4 and defines an opening 11 into the spark plug in alignment with the socket 5. An arcuate shaped gasket seat 12 is provided on the upper face of the flange 9, for a purpose to be hereinafter explained.

The ignition cable lead-in assembly indicated generally by the numeral 13 comprises an outer metal conduit 14, which may be in the form of flexible braid with a rigid metal ferrule 15 brazed or otherwise fixed to the spark plug end thereof; a coupling nut 16 swivelly engaging an external flange 17 on the ferrule and threadedly engageable with the spark plug barrel 6; and a cable 18 extending through the conduit 14 and beyond the spark plug end thereof into the socket 5 of the spark plug. The ignition conducting wire 19 within the cable 18 extends a short distance beyond the end of the insulating covering 20 thereon, into the upper end of a metal terminal member such as the eyelet 21 to which is secured a contact piece such as the coil spring 27 which resiliently bears against the upper end of the spark plug central electrode 7. For ease of assembly, the eyelet 21 is preferably provided with a U-shaped socket 22 in its upper end into which the end of the wire can be inserted and the upper portion of the eyelet then clinched around the same.

Encircling the cable 18 between the gasket seat 12 on the spark plug barrel 6 and the conduit ferrule 15 is an annular gasket or packing member 23, preferably made of spring steel for maximum resilience and good electrical conductivity. The lower annular portion of the packing member 23 is generally C-shaped in radial section as shown, and conforms with the curvature of the seat 12 and the flat bottom face of the flange 17 on the ferrule 15. Extending upwardly from the C-shaped section of the packing member 23, and integral therewith, is a short sleeve-like section 24 which is of somewhat larger internal diameter than the diameter of the cable 18 and has an internal flange 25 at its upper end which provides a sufficiently restricted passage for the cable as to firmly grip and effect a depression of the insulation 20.

Surrounding the portion of the cable extending into the spark plug is a resilient fluid-impervious sleeve 26 of soft rubber or like material, having an integral enlargement 28 shaped to conform with internal surface of the C-shaped section of the packing member 23. The sleeve 26 including its enlargement 28 is permanently bonded to the cable insulation 20, eyelet 21 and packing member 23, and is preferably formed by molding the rubber directly around the cable with the eyelet and packing member in place and using the internal flange 25 at the upper end of the packing member as a dam at that end.

In operation, with the coupling nut 16 tightened securely on the spark plug barrel 6, the C-shaped section of the packing member 23 is compressed between the flanges 9 and 17 on the conduit ferrule and spark plug barrel respectively, and by reason of its resiliency conforms sufficiently closely to the surface of each such flange as to effect both a moisture proof seal and continuous electrical bond therewith. On account of the rubber sleeve 26 being permanently bonded to the cable insulation and to the inner surface of the packing member 23, any moisture present within the conduit 14 or ferrule 15 is positively prevented from seeping into the spark plug, even should the rubber lose its resiliency after continued use. Further, by reason of the packing member 23 being made of spring steel or equivalent metal, it does not lose any appreciable amount of resilience with age.

I have thus provided a spark plug and ignition cable lead-in assembly incorporating not only a more effective and longer lasting seal against entrance of moisture into the spark plug, but also a more reliable electrical bond between the interconnected radio shielding sections of the spark plug and cable conduit.

I claim:

1. An ignition lead-in assembly adapted to cooperate with the socket-forming outer casing of a spark plug and the radio shielding conduit on the lead in effecting a waterproof joint therebetween, comprising an ignition conductor having an insulating covering, an electrically conductive eyelet member secured to one end of the conductor, an annular spring metal packing member encircling the insulating covering of the conductor and including an outwardly-closed elastically deformable C-shaped section, and a fluid-impervious sleeve of soft rubber or like elastically yieldable material surrounding the portion of the conductor between the eyelet member and the packing member and permanently bonded to the insulation covering and to each of said members.

2. An ignition lead-in assembly adapted to cooperate with the radio shielding shell of a spark plug and the radio shielding conduit on the lead in effecting a waterproof and electrically continuous shielding joint therebetween, comprising an elastically deformable metal gasket comprising an annular substantially flat portion having its outer extremities incurved to provide an outwardly convex portion, an insulated ignition conductor extending through the gasket and provided with a terminal member secured to the end thereof nearest the convex portion of the gasket, and a fluid impervious sleeve of soft rubber or like material permanently bonded to the terminal member and to the conductor insulation and having an integral enlargement permanently bonded to the inner surface of the gasket.

3. In a radio shielded spark plug and ignition lead connector assembly, a spark plug shielding barrel having an arcuately recessed gasket seating surface on its outer end face, an ignition conductor with an insulating covering thereon extending into the barrel and having a terminal carrying member electrically connected to its intruded end, a metal conduit surrounding the insulation on the conductor outside the barrel and provided with a substantially flat gasket seating surface opposite the outer end face of the barrel, a spring metal C-section gasket encircling the cable between and resiliently pressing against said seating surfaces, a fluid-impervious resilient sleeve having its inner surface permanently bonded to the conductor insulation and its external surface permanently bonded to and substantially filling the C-section of said gasket, and means for coupling the barrel and conduit together so as to compress the gasket therebetween.

4. An electrically continuous and waterproof joint between a spark plug radio shielding barrel and an ignition cable shielding conduit, comprising an internal flange at the upper end of the barrel provided with an inwardly and upwardly facing arcuate depression around the inner extremities thereof, a metal ferrule forming a continuation of the ignition cable shielding conduit and having a substantially flat external flange disposed opposite the internal flange on the spark plug, a coupling nut securing the cable conduit to the spark plug barrel, an annular metal packing member of spring steel having a cylindrical section internally flanged at its upper end to engage the insulation on the cable and an expanded internal-annulus-forming section at its lower end, the last named section consisting of a flat portion resiliently pressing against the external flange on the conduit ferrule and an arcuate portion resiliently pressing against the arcuate depression in the internal flange on the spark plug barrel, the internal surfaces of the packing member being permanently bonded to the cable insulation.

5. In combination, a radio shielding spark plug shell, a radio shielding lead-in conduit, an elastically deformable gasket of spring steel or the like having an annular portion of outwardly convex shape, oppositely disposed gasket seating surfaces on the spark plug shielding shell and lead-in shielding conduit, one of said seating surfaces being concave to receive and closely conform with said convex portion of the gasket, an insulated ignition conductor extending through the gasket, and a fluid impervious sleeve of soft rubber or like material permanently bonded to both the

conductor insulation and to the inner surface of said gasket convex portion.

6. An ignition lead-in assembly adapted to cooperate with the radio shielding shell of a spark plug and the radio shielding conduit on the lead in effecting a waterproof and electrically continuous shielding joint therebetween, comprising an elastically deformable metal gasket comprising an annular substantially flat portion having its outer extremities incurved to provide an outwardly convex portion, an insulated ignition conductor extending through the gasket, and a fluid impervious sleeve of soft rubber or like material permanently bonded to the conductor insulation and having an integral enlargement permanently bonded to the inner surface of the gasket.

7. An electrically continuous and waterproof joint between a spark plug radio shielding barrel and an ignition cable shielding conduit, comprising an internal flange at the upper end of the barrel provided with an inwardly and upwardly facing arcuate depression around the inner extremities thereof, a metal ferrule forming a continuation of the ignition cable shielding conduit and having a substantially flat external flange disposed opposite the internal flange on the spark plug, a coupling nut securing the cable conduit to the spark plug barrel, an insulated ignition cable in said conduit extending into said barrel, an annular metal packing member of spring steel having a cylindrical section internally flanged at its upper end to engage the insulation on the cable and an expanded internal-annulus-forming section at its lower end, the last named section consisting of a flat portion resiliently pressing against the external flange on the conduit ferrule and an arcuate portion resiliently pressing against the arcuate depression in the internal flange of the spark plug barrel, the internal surfaces of the packing

member being permanently bonded to the cable insulation.

8. An electrically continuous and waterproof joint between a spark plug radio shielding barrel and an ignition cable shielding conduit, comprising an internal flange at the upper end of the barrel provided with an inwardly and upwardly facing arcuate depression around the inner extremities thereof, a metal ferrule forming a continuation of the ignition cable shielding conduit and having a substantially flat external flange disposed opposite the internal flange on the spark plug, a coupling nut securing the cable conduit to the spark plug barrel, an insulated ignition cable in said conduit extending into said barrel, an annular metal packing member of spring steel having an expanded internal-annulus-forming section with a flat portion resiliently pressing against the external flange on the conduit ferrule and an arcuate portion resiliently pressing against the arcuate depression in the internal flange of the spark plug barrel, the internal surfaces of the packing member being permanently bonded to the cable insulation.
